US0D1102271S

(12) **United States Design Patent** (10) **Patent No.:** **US D1,102,271 S**
(45) **Date of Patent:** **** Nov. 18, 2025**

(54) **PACKAGING TRAY**

(71) Applicant: **Delta Electronics, Inc.**, Taoyuan (TW)

(72) Inventor: **Hui-Wen Tsai**, Taoyuan (TW)

(73) Assignee: **Delta Electronics, Inc.**, Taoyuan (TW)

(**) Term: **15 Years**

(21) Appl. No.: **29/932,048**

(22) Filed: **Mar. 11, 2024**

Related U.S. Application Data

(62) Division of application No. 29/858,865, filed on Nov. 4, 2022, now Pat. No. Des. 1,049,856.

(57) **CLAIM**

The ornamental design for a packaging tray as shown and described.

DESCRIPTION

FIG. 1 is a front perspective view of a packaging tray showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a plan view thereof, showing the packaging tray in an unfolded configuration;

FIG. 10 is a front perspective view of FIG. 1 thereof, shown in an alternate configuration of use; and,

FIG. 11 is a rear perspective view of FIG. 2 thereof, shown in an alternate configuration of use.

The evenly broken lines illustrate portions of the packaging tray that form no part of the claimed design. The dot-dash-dot lines represent fold lines that form no part of the claimed design.

1 Claim, 11 Drawing Sheets
